KERF-CUTTING MACHINE

Frank A. Lindgren, Western Springs, Ill., assignor
to Goodman Manufacturing Company, Chi-
cago, Ill., a corporation of Illinois

Application January 2, 1941, Serial No. 372,845

5 Claims. (Cl. 262—30)

This invention relates to improvements in kerf-cutting machines of the room and pillar type in which the cuttings are discharged from the rear end of the machine, and has for its principal object to provide a novel arrangement of parts so as to assist in clearing the cuttings from the machine and otherwise improve the design and operation of the machine.

As heretofore constructed, the conventional form of kerf-cutting machines of the character above referred to has a cutter bar arranged parallel with the longitudinal axis of the machine body, with a base plate extending beneath said bar throughout its length forming a cuttings channel opening to the rear end of the machine. The cuttings brought rearwardly by the cutter chain from the kerf tend to accumulate in and about the rear end of the machine in such large quantities that they usually have to be removed by hand shoveling. Moreover, some cuttings tend to be carried around the rear end of the cutter chain and returned to the kerf through the retreating side of the cuttings channel.

In carrying out my invention, I arrange the cutter bar at an angle to the longitudinal axis of the machine body, with its front end inclined toward the normal direction of cutting of the machine, and with the base plate of the machine cut laterally away from below the rear end of the cutter bar at the rear corner of the machine, so that the cuttings will be deposited directly on the mine floor both at the rear and along the retreating side of the machine. In this manner, the cuttings are spread over a relatively wide area as they are discharged from the machine, instead of being accumulated in a pile at the rear or side discharge openings of the machine. As a result, the need for hand shoveling is greatly reduced and in many instances entirely eliminated, and excess cuttings are not returned to the kerf along the retreating side of the cutter bar.

The invention may best be understood by reference to the accompanying drawings, in which

Figure 1 is a plan view of the machine, with a portion of the cutter bar omitted, and with parts of the gear casing broken away to show details of the mechanism therein;

Figure 2 is a side view of the machine, drawn to a slightly larger scale than Figure 1, with the cutter chain drive mechanism shown in longitudinal section;

Figure 3 is a rear view of the machine, with

parts of the gear casing broken away to show details of the feed mechanism;

Figure 4 is a bottom view of the machine, drawn to a smaller scale than the preceding figures, with a front portion of the bottom or base plate broken away;

Figure 5 is a diagram illustrating the manner of use of the machine in a mine.

Referring to the details of the embodiment of my invention illustrated in the drawings, the machine body indicated generally at 10 has a base plate 11, a cutter bar 12 extending forwardly of the machine with a cutter chain 13 movable thereabout as usual, a motor 14 mounted over the cutter bar at the front end of the machine, and a gear casing 15 at the rear of the motor and housing the feeding and the cutter chain drive mechanism.

The machine body is generally rectangular in shape, as usual, but the cutter bar 12 is arranged at a slight angle to said body, with its rear end disposed in the extreme rear corner at the retreating side of the machine body, and with its forward end projecting adjacent the center of the front end of the body, as shown in Figures 1, 4 and 5. With the arrangement shown herein, the machine is designed to cut from right to left, as is customary with machines of this character, so that the rear end of the cutter bar is in the rear right corner. If the machine is to cut in the opposite direction, the cutter bar will of course be disposed on the opposite, or left, side of the machine body, and in the reverse angular relation to that shown in the drawings. As shown in Figure 5, the extreme outer end of the cutter bar 12 preferably does not extend laterally substantially beyond the plane including the outermost limits of the advancing side of the machine body, so that the cutter bar will not interfere with usual movement of the machine while the latter is being dragged over the mine floor, or being loaded upon its truck or being transported about the mine on the latter.

The cutter bar 12 is supported, as usual, intermediate its ends between the base plate 11 and motor 14, as by opposed supporting brackets 17, 17, but the base plate 11 is cut away at the rear right corner of the machine body, so that the cutter chain 13, as it passes around its drive sprocket 18 at the rear end of the cutter bar, projects freely over the mine bottom and is wholly open to the rear and the retreating side of the machine, as clearly shown in Figure 4. The base plate projects beneath the cutter bar at the right front corner of the machine, to assist in main-

taining lateral balance of the machine as a whole on said base plate. The motor 14 may be partially supported on said right front corner of the base plate by a short upright front wall section 19. The cutter bar projects from an opening 20 formed between the front wall section 19 and the front wall section 21 at the left side of the machine. An upright wall or partition 22 along the left or advance side of the cutter bar provides a cuttings discharge passage 23 disposed at the same angle as said cutter bar and opening to the rear right corner of the machine body, as shown in Figures 3 and 4.

The arrangement of the cutter bar as described provides room at the rear advance portion of the machine body for a casing section 15a enclosing the feed gearing, and at the front advance portion for a casing section 15b for enclosing a motor rheostat, controller, or other electrical equipment.

It will be especially noted that the casing sections 15a and 15b extend the full height of the machine, so as to accommodate the required feed gear reduction mechanism, thereby giving substantially more vertical space than is usually afforded in ordinary room and pillar machine designs, wherein most of the gear reduction mechanism must be crowded in the space above the cuttings discharge passage. As a result of the advantageous arrangement of gearing space herein disclosed, it is possible to reduce the overall height of the machine to a minimum, which is determined only by the height of the motor and the cuttings discharge passage 23, and also to shorten the machine lengthwise so that it can be readily maneuvered for cutting in narrow spaces, as for instance, between mine props and the working face.

In the form of feed gear reduction mechanism shown herein, the armature pinion 24 is meshed with gear 25 on longitudinal shaft 26, having suitable bearing in the casing section 15a above and toward the advance side of the cuttings discharge passage, as shown in Figure 3. A worm 27 is fixed on shaft 26, and is meshed with a relatively large worm gear 28 keyed on a transverse shaft 29. The latter shaft has suitable bearing in the casing section 15a at one side of the cuttings channel 23, and has a sun gear 30 at its outer end forming part of a two speed planetary gear device indicated generally at 31.

The form of planetary gear 31 shown herein is of the same type commonly used in kerf-cutting machines, so it need not be described in detail, excepting to point out that the planetary gears 32, 33 of different pitch diameters and rotatable together in a cage member 34, are meshed respectively with internal gear members 35 and 36, respectively. The internal gear member 36 has a hub 37 keyed on driven shaft 38. The periphery of cage member 34 encloses the gear member 36, and has a friction band 39 thereabout. A similar friction band 40 surrounds the internal gear member 35. The arrangement is such that by loosening band 39 and tightening band 40 so as to restrain cage 34 from rotation, the shaft 38 will be driven at low speed. By loosening band 40 and tightening band 39, the latter member 36 will be restrained from rotation with the result that shaft 38 will be driven at high speed.

The driven shaft 38 has bearing in the side wall 42 of the casing section 15a and has a spur gear 43 keyed on its outer end, meshed with an internal gear member 44 having a hub 45 rotatable on a stub shaft 46. A winding drum 47

has hub 48 rotatably mounted on the hub 45, and is provided with a pin clutch member 48a of the usual form adapted to be engaged at will in one of a plurality of cooperating holes 49 in the face of the internal gear member 44. A cable 50 is carried by the drum 47 and is adapted to be trained as usual about a sheave 51 at the front leading corner of the machine body, for feeding the machine laterally along the working face, or 10 to be trained rearwardly about a sheave 52 or about said last named sheave and a sheave 53 disposed centrally of the machine and at the rear end thereof, for maneuvering the machine in various directions over the mine floor or loading 15 the machine upon its transporting truck in the usual manner.

The worm shaft 26 is extended and has a coupling pocket 60 at its rear end adapted to be engaged as usual by a coupling member of a mine truck (not shown), for propelling the latter when the machine is mounted thereon.

The machine is also provided as usual with a suitable retarding device, herein consisting of a friction-controlled cable drum 55 of the usual form, rotatably mounted on a shaft 56 extending 25 longitudinally from the rear end of the machine casing 15 adjacent the retreating side of the machine, so its cable 57 can be trained directly to a suitable anchor, if desired.

30 The drive connections from the motor 14 to the cutter chain sprocket 18 includes a gear 61 on a stub shaft 62 meshed with the armature pinion 24. In the arrangement shown, the stub shaft 62 is offset toward the right side of the machine, so as to be disposed on an axis intersecting the axis of the cutter chain sprocket. A bevel pinion 63 is fixed on shaft 62 and is meshed with a large bevel gear 64 having a flanged hub 65 supported by suitable bearings 40 66 and 67 on the upright sprocket shaft 68. The latter shaft in turn has suitable bearings 69 and 70 in the gear case 15. A clutch 71 is provided for connecting the hub 65 with sprocket shaft 68, as herein shown, said clutch consisting of a 45 sliding sleeve 72 mounted on said hub and having depending clutch jaws 73 passing downwardly through the flanged portion of said hub so as to engage in cooperating clutch teeth formed in the periphery of a collar 74 fixed on the sprocket shaft. The clutch sleeve 72 may be shifted as usual by means of a shifter collar 75, engaged by a shifter yoke 76 on rocking shaft 77 extending through the side of the housing 15 and operated by control handle 78.

55 Several advantages of the arrangement of parts above described will now be manifest. The arrangement of the cutter bar with its discharge end entirely open to the bottom, rear, and along the retreating side of the machine body greatly 60 facilitates the rapid discharge of cuttings from the machine, so as to reduce and in many cases, entirely eliminate, the necessity of shoveling the cuttings away from the machine. The offset arrangement of the cutter bar and cuttings discharge passage also provided more ample and convenient space for the gear reduction mechanism, thereby permitting the machine body to be made of minimum height and width, as hereinbefore explained. The angular arrangement 65 of the cutter bar as it projects at the front of the machine has the further advantage of facilitating the sumping, cross cutting, and withdrawal of the machine, as illustrated in Figure 5. The machine can readily be sumped substantially the full length of its cutter bar, without interference 70

of the machine body with either the working face F or the side wall or rib R, as shown in the dotted line position of the machine. While cutting across the face F, as shown in the full line position, the slight angular inclination of the cutter bar in the direction of cutting, combined with the fact that the cutter chain is moving toward the machine on the advancing side of the cutter bar, has a distinct tendency to stabilize the machine and reduce the amount of retardation necessary to maintain it at the proper cutting angle relative to the face. Finally, it will be understood that the machine can be withdrawn at the end of the cross cut by moving it almost parallel with the rib, instead of at a substantial angle thereto, as is usually necessary with present room and pillar machines.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a kerf-cutting machine, a frame supported on a base plate for universal movement over a mine floor, a cutter bar projecting from the front end of said frame at a fixed obtuse angle to the longitudinal axis thereof, a cutter chain orbitally movable about said cutter bar, the rear portion of said cutter chain projecting beyond said base plate to the rear and one side of the latter, and flexible feeding means for advancing said machine laterally along a coal face so that the cuttings brought back longitudinally through the frame will be discharged freely at the rear and along the retreating side of the latter.

2. In a kerf-cutting machine, a frame supported on a base plate for universal movement over a mine floor, a motor on said frame, a cutter bar projecting from the front end of said frame at a fixed obtuse angle to the longitudinal axis thereof and extending beneath said motor, a cutter chain movable orbitally about said cutter bar

5 and driven by said motor, the rear portion of said cutter chain extending beyond said base plate to the rear and one side thereof, and flexible feeding means for advancing said machine laterally along a coal face so that the cuttings brought back by said cutter chain will be discharged freely at the rear and along the retreating side of the latter.

10 3. In a kerf-cutting machine, a frame slidable on its own bottom on the mine floor, a chain carrying cutter bar extending in an angular direction with respect to the longitudinal axis of said frame, from a position adjacent the rear retreating portion of said frame, and projecting 15 from adjacent the center of the front end of said frame at an obtuse angle to the longitudinal axis of said frame, and flexible feeding means for advancing said machine laterally along a coal face including gear reduction mechanism mounted on the rear end of said frame with a portion thereof disposed at one side of said cutter bar and in the same horizontal planes as the latter.

20 4. In a kerf-cutting machine, a generally rectangular frame slidable on its own bottom on the mine floor, a chain carrying cutter bar projecting from the front end of said frame at a fixed obtuse angle to the longitudinal axis of said frame, with its rear end disposed in one rear corner of said frame and open to the rear and 25 adjacent side of said frame, and with its front end disposed substantially in a line extended along the opposite side of said frame, and flexible feeding means for advancing said frame laterally along a coal face to cut a kerf, with said 30 cutter bar inclined in the direction of cutting.

35 5. In a kerf-cutting machine, a frame slidable on its own bottom on the mine floor, a chain carrying cutter bar projecting from adjacent the center of the front end of said frame and at an obtuse angle to the longitudinal axis of said frame, a motor on said frame over said cutter bar, and flexible feeding means driven by said 40 motor for advancing said machine laterally along a coal face including gear reduction mechanism mounted at the rear end of said motor with a portion thereof disposed on the advance side of said cutter bar and in the same horizontal plane as the latter.

FRANK A. LINDGREN.
